UNITED STATES PATENT OFFICE.

ALBERT A. UNRUH, OF PORTLAND, OREGON, ASSIGNOR OF ONE-THIRD TO RAYMOND W. FAIRFOULL, OF PORTLAND, OREGON, AND ONE-THIRD TO MICHAEL T. SNYDER, OF NEW ORLEANS, LOUISIANA.

ANTISLIPPING DEVICE FOR SHOES.

1,274,110.

Specification of Letters Patent. Patented July 30, 1918.

Application filed March 1, 1918. Serial No. 219,849.

To all whom it may concern:

Be it known that I, ALBERT A. UNRUH, a citizen of the United States, residing at Portland, in the county of Multnomah and State of Oregon, have invented certain new and useful Improvements in Antislipping Devices for Shoes; and I do declare the following to be a full, clear, and exact description of the invention, such as will enable others skilled in the art to which it appertains to make and use the same.

My invention has for its principal object to provide an extremely simple and inexpensive, yet a highly efficient and durable anti-slipping device or toe calk designed primarily for use upon athletic shoes of all sorts although it could well be employed on other shoes as an ice creeper.

Another object of the invention is to provide the calk with a resilient tongue for cleaning it of dirt and the like with which it would otherwise be clogged; and in this connection a still further object is to secure the cleaning tongue in place in a novel manner so that it may be readily removed whenever necessary.

With the foregoing general objects in view, the invention resides in the novel features of construction and unique combinations of parts to be hereinafter fully described and claimed, the descriptive matter being supplemented by the accompanying drawings which form a part of this specification and in which:

Figure 1 is a perspective view of the invention applied to a shoe;

Fig. 2 is a longitudinal section of the device;

Fig. 3 is a perspective view of the invention detached from the shoe;

Fig. 4 is a perspective view of the U-shaped calk; and

Fig. 5 is a similar view of the calk cleaning tongue.

In the drawings above briefly described, the numeral 1 designates a U-shaped calk formed of a single piece of metal and having lateral ears 2 on its upper edge for securing it to the shoe sole, the lower edge of said calk being sharpened at 3 to penetrate the earth; and this edge preferably inclines upwardly and rearwardly as shown most clearly in Fig. 2. The ends of the U-shaped calk 1 are rigidly connected by a transverse rod 4,

and spaced inwardly from this rod, the upper edge or any other suitable portion of the calk, is provided with a pair of internal lugs 5 which are preferably formed integrally therewith and bent into position as shown in the drawings.

A calk cleaning member in the form of a spring metal tongue 6 is disposed between the arms of the calk 1 and is shaped to engage said arms and in fact the entire length of the calk at its edges. The rear end of the tongue 6 is bent upwardly and forwardly at 7 around the rod 4 and then extends forwardly a suitable distance from this rod to form a spring catch 8 underlying the lugs 5 to anchor the rear end of the tongue, this end being bent upwardly to form a flange 9 to engage the front edges of said lugs so that rearward movement of the tongue is prevented. Outward movement of the front end of tongue 6 is prevented by a lug 10 preferably bent inwardly from the lower edge of the calk 1, and although only one of these lugs is shown, it will be obvious that any preferred number could be employed. Furthermore, it may be expedient in some cases to provide other means for preventing excessive outward movement of the tongue.

In use, the tongue 6 yields upwardly each time the foot is lowered upon the ground thus exposing the calk 1 for anti-slipping engagement with the earth or ice. The moment the foot is raised, however, the resiliency of the tongue 6 returns the latter to its lowermost position and thus any matter which would otherwise accumulate in and clog the calk, will be discharged from the latter so that it is kept clean and efficient at all times. Whenever it is necessary to remove the tongue 6, the entire calk must be detached but it is then a simple matter to depress the spring catch 8 so that its flange 9 will disengage the lugs 5, after which the entire tongue may be shifted rearwardly to simultaneously disengage the lug 10 and the rod 4.

The device is extremely simple and inexpensive yet it will be obvious that it will be highly efficient and durable either as an athletic calk or as an ice creeper. Furthermore, although the calk is shown only on the toe of the shoe sole, it will be understood that it could also be employed on the heel if required. On account of its ad-

vantages, the construction shown and described is preferably employed, but within the scope of the invention as claimed, numerous minor changes may well be made.

5 I claim:

1. An anti-slipping device for shoes comprising a U-shaped calk, means for securing said calk to the shoe sole, an upwardly yielding cleaning member between the arms 10 of said calk, and a releasable spring catch for holding said cleaning member in place.
2. A structure as specified in claim 1, said cleaning member being constructed of spring metal and said catch being formed of a portion 15 of said member.
3. An anti-slipping device for shoes comprising a U-shaped calk, means for securing said calk to the shoe sole, a rod extending transversely between the ends of 20 said calk and secured thereto, a pair of internal lugs extending from said calk ends and spaced inwardly from said rod, a spring metal calk cleaning tongue between the arms

of said calk and having one end bent upwardly around said rod and forming a releasable spring catch, said catch engaging said lugs to anchor one end of said tongue, and means for preventing outward movement of the other end of said tongue beyond said calk.

25

4. An anti-slipping device for shoes comprising a U-shaped calk, means for securing said calk to the shoe sole, an upwardly yieldable spring metal calk cleaner between the arms of said calk, said cleaner having its rear end bent to form a spring catch, and means coacting with said spring catch to detachably secure the cleaner in place.

30

4. An anti-slipping device for shoes comprising a U-shaped calk, means for securing said calk to the shoe sole, an upwardly yieldable spring metal calk cleaner between the arms of said calk, said cleaner having its rear end bent to form a spring catch, and means coacting with said spring catch to detachably secure the cleaner in place.

35

5. In testimony whereof I have hereunto set my hand in the presence of two subscribing 40 witnesses.

ALBERT A. UNRUH.
